United States Patent Office

Des. 195,028

Patented Apr. 16, 1963

195,028

TILE

Wallace Lanz, New York, N.Y., assignor to Minnesota and Ontario Paper Company, Minneapolis, Minn.

Filed June 12, 1962, Ser. No. 70,515

Term of patent 14 years

(Cl. D18—2)

FIG. 1

I claim:

The ornamental design for the tile, substantially as shown and described.
